United States Patent Office

Des. 223,099
Patented Mar. 7, 1972

223,099

BATTERY CHARGER

Stephens N. Sato, San Diego, Calif., assignor to Ivac Corporation, San Diego, Calif.

Filed Sept. 25, 1970, Ser. No. 25,188

Term of patent 14 years

Int. Cl. D13—02

U.S. Cl. D26—15

Fig. 5

Fig. 6

FIG. 1 is a perspective view of a battery charger embodying my new design;

FIG. 2 is a side elevation as seen from the left of FIG. 1;

FIG. 3 is a front elevational view of the battery charger shown in FIG. 1;

FIG. 4 is a rear elevational view of the battery charger shown in FIG. 1;

FIG. 5 is a top plan view of the battery charger shown in FIG. 1; and

FIG. 6 is a bottom plan view of the battery charger shown in FIG. 1.

I claim:

The ornamental design for a battery charger, as shown.
